UNITED STATES PATENT OFFICE.

FRANK T. POWERS, OF NEW YORK, N. Y.

MEANS FOR COOLING PHOTOMECHANICAL PRINTING PLATES.

Application filed March 31, 1921. Serial No. 457,381.

To all whom it may concern:

Be it known that I, FRANK T. POWERS, a citizen of the United States, residing in the city and State of New York, have made 5 certain new and useful Improvements in Means for Cooling Photomechanical Printing Plates, of which the following is a specification.

The invention relates to a novel device or 10 mechanism for cooling photo-mechanical printing plates, and more especially to a novel device or mechanism for cooling such plates by the application thereto of a cooling fluid, in which mechanism there is provided 15 a novel form of support for the plates to be cooled, and also means for quickly applying a cooling fluid to the plate and quickly withdrawing it therefrom, so as to vary and control the action of the cooling fluid upon 20 the plate.

Objects and advantages of the invention will be set forth in part hereinafter and in part will be obvious herefrom, or may be learned by practice with the invention, the 25 same being realized and attained by means of the instrumentalities and combinations pointed out in the appended claims.

The invention consists in the novel parts, constructions, arrangements, combinations 30 and improvements herein shown and described.

The accompanying drawings, referred to herein and constituting a part hereof, illustrate one embodiment of the invention, 35 and together with the description, serve to explain the principles of the invention.

Of the drawings:

Fig. 1 is a vertical central section through 40 a cooling device embodying the invention; Fig. 2 is a fragmentary top plan of one form of plate support, and having passages for the cooling fluid, these devices being of the same form as is shown in Fig. 1;

Fig. 3 is a fragmentary vertical section, 45 corresponding generally to the upper part of Fig. 1, but showing a somewhat different form of mechanism for actuating and controlling the cooling fluid, and showing also a different form of plate supporting means;

Fig. 4 is a detached, fragmentary top plan, 50 on an enlarged scale, of the form of plate support and fluid passages shown in Fig. 3;

Fig. 5 is a vertical section taken on the 55 line 5-5 of Fig. 4;

Fig. 6 is a plan, like Fig. 2, but showing

a different arrangement of the fluid-passing orifices;

Fig. 7 bears a like relation to Fig. 1;

Fig. 8 bears a like relation to Fig. 3; and 60

Fig. 9 is a central, vertical section of a form of mechanism in which the plate support is movable into and out of the fluid in the reservoir.

Photo-mechanical printing plates are 65 made usually from a plate of copper or other suitable metal, which is usually relatively thin as compared to the ordinary height of types or plates for printing presses, and during the process of making 70 these plates, they are subjected to heat, as in the well known "enamel" process. It is desirable to cool the heated plate rapidly and at the same time to have the cooling means within the control of the workman, 75 so that he may accurately vary and control the duration and degree of the application of the cooling fluid to any particular plate.

In the present preferred embodiment of 80 this invention, plate supporting means are provided comprising a relatively large number of plate supports of comparatively small area with respect to the area of the photo-mechanical plate, these supports being separated from each other but in close proximity to each other, and between such supports are passages for the cooling fluid toward and from the photo-mechanical plate upon the supports. Cooperating with the plate supporting means, there are provided 85 means under the direct and immediate control of the workman, for quickly applying to and withdrawing from the plate the cooling fluid, and for varying and controlling the degree of action of the cooling fluid upon 90 the plate.

Referring now in detail to the present preferred embodiment of the invention, and referring to the plate support shown in Figs. 1 and 2, this support has a base 1, 100 and projecting upwardly therefrom are the plurality of plate supporting members already referred to. As shown these consist of upwardly projecting, relatively narrow ridges or flanges 2, extending upwardly 105 from the base plate 1. These supports are preferably of circular or annular form, as best appears from Fig. 2, these circles or annuli being preferably concentric and spaced apart, the fluid passages through the base 1 being located therebetween. The base plate 1 is shown of rectangular form, 110

and the exterior supports 2, near the corners of base 1, are segments concentric with the other supporting members 2. In the spaces 3, between the supporting members 2, there are in the base 1 a plurality of orifices 4, through which the cooling fluid flows to and from the plate to be cooled.

In Figs. 3, 4 and 5 a different form of plate supporting means is shown. In these figures a base plate 7 is provided, and projecting upwardly therefrom are a plurality of pins or fingers 8, upon which the photo-mechanical plate is supported during the cooling operation, these studs or fingers 8 having relatively small supporting surfaces, and are spaced apart but closely contiguous to each other, and interspersed or interposed between the supports are passages 9 through the base 7, for the passage of the cooling fluid. It will be understood that both these forms of plate supports are illustrative and not restrictive of the invention.

The particular form of means for supplying and controlling the cooling fluid shown herein, so far as concerns certain features thereof, is substantially the same or similar to that shown in my Patent No. 1,373,909, but in other features thereof it is different both as to structure and operation. It will be understood, so far as concerns many features of the invention, that other kinds of controlling means for the cooling fluid may be provided.

In the embodied form of means for supplying and controlling the action of the cooling fluid, and referring now to Figs. 1 and 2, the base 1 of the plate support is seated on a shoulder 12 in a pan 13, so that the base 1 of the support forms a closure over the lower portion of the pan 13 except for the fluid passing orifices 4. The part of the pan 13 beneath the base plate 1 constitutes a fluid chamber 14, and the normal top level of the cooling fluid will be not higher than the base plate 1 or 7, or possibly a little higher or lower. The level of the tops of the supports and the edge of the pan will be determined to secure the best practical results. Usually the edge of the pan will be just a little higher than the tops of the supports.

In this embodied form of means for applying to, withdrawing from, and controlling the action of the cooling fluid upon the photo-mechanical plate to be cooled, devices are provided for forcing additional fluid into the fluid chamber 14 and thence through the orifices 4. The bottom 15 of the pan 13, which also constitutes the bottom of the fluid chamber 14, is provided with an orifice 16, normally closed by a lift valve 17, which is guided and held in place by a guide 18, projecting downwardly from the bottom of the base 1, and working between guiding members 19 and 20 formed

on the valve. Beneath or otherwise adjacent to the fluid chamber 14 are the means for forcing the cooling fluid into the chamber 14. As embodied, an expansible and contractible fluid driving chamber 24, the top thereof being the bottom 15 of the chamber 14, and the side walls thereof formed by an annular rim 25, extending downwardly from 15, is operated by the workman to control the action of the cooling fluid. The bottom of the chamber 24 consists of a flexible diaphragm 26, movable to change the size or volume of the chamber, to effect the fluid flow into the chamber 14. Orifices 38 in the wall of the pan 13 discharge the water from the pan.

In connection with the foregoing a tank or reservoir is preferably provided for a permanent supply of the cooling fluid, the device being thus independent of hydrant or other water connection, if desired, and also readily movable from place to place as found convenient. As embodied, this tank 27 surrounds and supports the mechanism and devices already described. The bottom 28 of the tank has a central opening in which the diaphragm 26 is located, the edges of the diaphragm being secured between the bottom flange of the part 25 and the edge of the tank about the orifice, by rivets, bolts, or other suitable clasping means 29, to form a fluid-tight connection.

The embodied form of actuating means for the diaphragm 26 are foot operated, thereby leaving the hands of the workman entirely free. As embodied, a plate 30 preferably of somewhat spheroidal form is located beneath the diaphragm 26 and a rod 31 extends downwardly from the plate. This rod is pivotally connected at its bottom end 32 to a foot lever 33, which is pivotally supported at 34. A strap, bracket or pan 35 is fastened to the bottom of the tank 27, and is apertured to serve as a guide for the rod 31. A one-way valve 36 of suitable form, is located in the wall 25, to permit the inflow of water or other cooling fluid from the tank 27 into the chamber 24.

In operating the device, the photo-mechanical printing plate to be cooled is supported in part or entirely upon the plate supports, and the workman places his foot upon the pedal 33, and forces the plate 30 and diaphragm 26 upwardly, forcing the water from chamber 24 through the orifices in the plate support and against the under side of the plate. The beginning of this motion is shown in Fig. 1, which shows the valve 17 open and the valve 36 closed. When pedal 33 is released, plate 30 and diaphragm 26 descend, and valve 36 opens and valve 17 closes, the cooling fluid during such movement flowing in from the tank 27 into the chamber 24. The beginning of this movement is shown in Fig. 3 of the drawings.

When the valve 17 is employed, spilling orifices 38 will permit the water to flow from above the base plate 1 back into the tank 27, but at a rate which will not interfere with the supply of cooling fluid to the plate by the action of the foot lever 33. If desired, the valve 17 may be dispensed with, in which case the spilling orifices 38 may also be dispensed with.

10 In Fig. 3 a somewhat different form of the actuating and controlling means for the cooling fluid is shown. In this form, the valve 17 is omitted. The chamber 24 is contracted to drive the cooling fluid upwardly into contact with the plate to be cooled, and the subsequent expansion of the chamber draws the fluid directly downward by the same way it went up. The orifices 38 in this case are unnecessary, and the tank 27 merely provides a reserve supply or larger volume of the cooling liquid, as the water is not discharged thereinto from the pan 13. The valve 36 may be operated by hand if desired to control or equalize the quantity or level 25 of water between tank 27 and the fluid chambers 24 and 14.

With this mechanism the workman can, by the distance and duration of the foot movement, accurately control the rise of the liquid 30 against the plate, the duration of the contact of the cooling liquid with the plate, and the withdrawal of the liquid from the level of contact, either to terminate the cooling of a given plate, or in preparation for the quick 35 substitution of a subsequent plate in cooling position. The level of the cooling liquid can be very quickly lowered. There is thus provided a very nicely adjusted and controlled and a very rapidly operating plate cooling 40 mechanism.

In Figs. 6 and 7 a mechanism is shown of the same general construction as that of Figs. 1 and 2, already described, but different therefrom in certain of its features. In 45 Figs. 6 and 7, the annular supports 2 have their tops at or substantially at the level of the top edge of the pan 13, and the discharge orifices 38 are omitted, the discharge of the cooling fluid in this case being over the edge 50 of the pan 13 into the reservoir or tank 27. The openings 4 are also shown located only in the central part of the bottom of the pan 13.

In Fig. 8 a pan is shown having plate supports of the form shown in Figs. 3 and 4, but in Fig. 8 the tops of the supports 3 are substantially level with the edge of the pan 13. The openings 9 are located only in the central part of the bottom of pan 13.

60 In Fig. 9 a modified construction is shown, in central vertical section, wherein the plate supporting devices are vertically movable to and fro within the fluid reservoir to effect and control the action of the cooling fluid upon the plate. In the em-

bodied form thereof, a plate support or pan 40 (shown of the general form of those in Figs. 1 and 3) is provided, having a plurality of plate supporting members 41, extending upwardly from its bottom. The 70 bottom is provided with fluid passing orifices 39. The pan 40 is pivotally hung from the inner ends of a plurality of levers 42 and 43, preferably in pairs at opposite sides thereof. 75

The pairs of levers 42 and 43 are pivotally mounted, respectively, at 44 and 45 on the top edges of a tank or reservoir 46. Connected to the outer ends of the levers 44 and 45, respectively, are pivoted rods 47 and 48, 80 which rods are also pivoted, respectively, to arms 49 and 50, fixed to shafts 51 and 52, journaled on the frame.

To operate this mechanism, as embodied, 85 an arm 53 is fixed to shaft 50 and an arm 54 is fixed to shaft 51, and these arms are connected together by a pivoted link 55. A spring 56 is connected in tension between rod 55 and the machine frame to maintain the plate support 40 in its elevated position 90 as shown in Fig. 9.

The device is preferably foot operated so as to leave the hands of the workman free. As embodied, an arm 57 is fixed to shaft 51, and a link 58 is pivoted to arm 57. Link 58 95 is pivoted at 59 to a foot lever 60, which is pivotally mounted at 61. A stop 62 cooperates with spring 56 to position the plate support 40 in its elevated position.

The manner of operating will be clear. By 100 pressing pedal 60, the workman depresses pan or support 40, against spring 56, and thus can accurately and quickly control the action of the cooling fluid, passing through the orifices 39, upon the plate to be cooled as 105 it rests upon supports 41. When the workman releases the lever 60, the plate support and the plate are elevated out of the cooling fluid. The fluid openings could be located elsewhere than in the bottom of the support. 110

It will be understood that all the modifications and variations in form shown and described are exemplary, and are not restrictive of the invention, and that other changes may be made within the scope of 115 the accompanying claims without departing from the principles of the invention and without sacrificing its chief advantages.

What I claim is:—

1. A device for cooling photo-mechanical printing plates including a base plate provided with openings therein and having thereon a plurality of upstanding, spaced apart plate supports with open, unobstructed space thereabove, and means for causing a cooling fluid to pass through the openings in said base plate. 120

2. A device for cooling photo-mechanical printing plates including a base plate provided with openings therein and having 130

thereon a plurality of upstanding, spaced apart plate supports having their upper ends terminating in the same substantially horizontal plane with open, unobstructed space 5 thereabove, and means for causing a cooling fluid to pass through the openings in said base plate.

3. A device for cooling photo-mechanical printing plates including, in combination, 10 a pan having open, unobstructed space thereabove and having a foraminate bottom and

also having thereon a plurality of small, upstanding, spaced apart plate supports closely adjacent to each other, and means for supplying cooling fluid to said pan and for varying the level of said cooling fluid within 15 said pan to control its cooling action on said plate.

In testimony whereof, I have signed my name to this specification.

FRANK T. POWERS.
